CHRISTOPHER HENRY SNYDER, OF BERKELEY, CALIFORNIA.

MEANS FOR HOLDING REINFORCING FABRICATION OF CONCRETE FLOORS AND SLABS.

Application filed October 5, 1920. Serial No. 414,908.

To all whom it may concern:

Be it known that I, CHRISTOPHER HENRY SNYDER, a citizen of the United States, and a resident of Berkeley, county of Alameda, 5 and State of California, have invented a new and useful Means for Holding Reinforcing Fabrication of Concrete Floors and Slabs, of which the following is a specification.

10 This invention relates to concrete construction, and particularly to a method and means for facilitating the emplacement of the reinforcing rods and fabrication.

15 Among the various systems for the erection of reinforcing fabrication for concrete structures, a common and popular form of such fabrication is well known as the "Continuity mat system," in which a mat-like fabrication of reinforcing rods is 20 arranged over the bottom surface of a mould, the ordinary practice being to place shoes or blocks in detached relation to and upon the bottom surface of the mould, or form, at predetermined positions with respect to a slab or floor element, and to loosely place upon the tops of these blocks, 25 shoes or chairs parallel and right angularly disposed reinforcing rods to form a rectangular bed frame wired at the superposed and overlapping portions together on the 30 tops of the chairs. Thereafter other parallel and right angular reinforcing rods are arranged upon the rectangular frame thus formed, the several rods being tied or 35 clipped together by suitable means at their crossing points. This forms a fabrication of which the elements while secured to each other, are not secured to the relatively loose blocks, shoes or chairs.

40 It is an object of the present invention to provide a novel method and system for positively connecting the given elements of the fabrication to their supporting chairs, so that after the fabricated mat has been 45 erected and its elements wired together, the whole, including the chairs, or supporting means, is rigidly interconnected and movable as a body.

It is further an object to provide a 50 method and means at once simple, substantial, practicable, involving the desired rigidity, and at the same time one that is highly economical in cost of practice and in cost of the elements forming the supports.

55 It is also an object to provide such a method and system with supporting means

that may be utilized readily in the supporting of reinforcing bars or members of various other systems of fabrication, as well as particularly adapted to the supporting of 60 fabrication of the "continuity mat system."

Another object of the invention is to provide a supporting and holding means capable of being manufactured at extremely 65 low cost in quantity and capable of being compactly arranged or nested to facilitate and maintain low cost of transportation from the time of manufacture until ultimately set up.

The invention possesses other objects and 70 features of advantage, some of which, with the foregoing, will be made manifest in the following description of the preferred form of the invention which is illustrated in the drawings accompanying and forming part 75 of the specification. It is to be understood that it is not intended to limit the invention to the embodiment shown by the said drawings and description, as variations may be adopted within the scope of the invention 80 as set forth in the claims.

In the drawings:

Figure 1 is a perspective of a preferred form of the supporting device, showing reinforcing bars applied and connected 85 thereto.

Figure 2 is a perspective of the supporting device before the application thereto of the rods and before the bending of the retaining means.

Figure 3 is a diagrammatic elevational view illustrating the packing of a plurality of supporting devices.

Figure 4 is a perspective of a somewhat modified form of the supporting device, 95 showing the reinforcing bars applied and connected thereto; and

Figure 5 is a perspective of the device of Fig. 4 before the attachment of the reinforcing bars and before the bending of the 100 connecting means.

Figure 6 is a perspective of the lower portion of one of the devices with the foot forming flanges provided with tacks.

Since the method now commonly in practice of erecting concrete reinforcing fabrication of the "continuity mat system" is well known, the same is not described in detail herein, and only a portion of the reinforcing elements are shown here, this being 110 sufficient to indicate the utility of the present method and system. The device of the pres-

ent invention, which will hereinafter be referred to as the "supporting clip", comprises a substantial chair, or standard-forming portion, most economically made of sheet material cut to predetermined shape and folded or bent to give rigidity and security and afford a desirable area and form of base. The upper end of the supporting clip is provided with seat-forming shoulders and with 10 contiguous and preferably integrally formed bendable tongues to be folded over reenforcing bars when applied to the supporting shoulders. The invention may be embodied in a plurality of forms of supporting standards and clips, as, for instance, the standards may have an angular cross-section, or a semi-circular cross-section, or may be of channel iron, or of various other shapes possessing the desired transverse rigidity, and 15 which, at the same time, will permit of a compact packing or nesting of the supporting clips for obvious reasons.

One form of the supporting clip is illustrated in Figs. 1, 2 and 3, in which the standard portion of the clip is punched or cut from sheet material, or from angle iron material, and, therefore, presents right angular, integrally connected flanges 2—2 of any suitable dimensions that may be desired, according 20 to the work in hand, the lower ends of the flanges 2—2 being shown as provided with outwardly turned foot-forming portions 3—3 to give stability to the standards. The upper ends of the flanges 2—2 are provided 25 with tongues 4 and 5, one for each flange, these tongues being materially narrower than the width of their flanges and spaced meditately between the longitudinal edges of the flanges and the intersecting angle 6 30 thereof.

It is desirable to provide a substantial support in the form of shoulders, or seats, upon which may be supported in superposed relation mat-forming reenforcing bars A and B, which are shown as disposed at right angles 45 to each other in Fig. 1. Therefore, the upper ends of the flanges 2—2, forming the standard, are formed with shoulders to receive the respective bars A—B, these shoulders being disposed substantially as follows: One of the flanges 2 is provided with a notch 7; extending inwardly and above this notch the flange is cut away on a transverse line 8, forming a seat, or shoulder, terminating at 50 the intersection of the side line 4^a of the tongue 4, and the other flange 2 is provided adjacent the angle 6 with a transversely extending shoulder, or seat-forming edge 9, in the same line or plane as the seat 8, so that 55 when the mechanic on the job turns the wing 10 from the position shown in Fig. 2 to the position shown in Fig. 1, the seats 8 and 9 become parallel to each other in the same plane and the reenforcing bar A may then be 60 laid in position across these seats, being 65

abutted on one face by the lower portion of the tongue 4, which extends above the seat 8, while on the other face the bar A is abutted by the contiguous surface of the edge 11 of the tongue 5 extending upwardly from the seat 9. The tongue 4 is then bent along the line 4^b over the top of the bar A and is then again bent along the line 4^c down the side of the bar A and its end is folded on the line 4^d inwardly under the bar, thus forming a 75 substantial hook over-hanging the interposed bar A and clinching it to its seats 8—9.

This operation performed, the mechanic may then apply the upper reenforcing rod B to respective seats, one of which is formed by the top edge 12 of a bendable wing 13 on one of the flanges 2, and which is relative to the tongue 5. The bendable wing 13 may have been bent in on the job at the time of the in-folding of the wing 10, and therefore would be ready to receive the applied bar B, which will rest above the bar A, the top of which is in the plane of the seat 12 adjacent the tongue 5, and also will bear upon a seat or transverse shoulder 14 contiguous to the tongue 4 and extending inwardly therefrom toward the line of the angle 6. The upper reenforcing bar B, having been applied, the tongue 5 is folded along the line 5^a over the top of the bar B and then is again folded along the line 5^b down the inside face of the bar B, thus forming a substantial clip clinching the bar B to its seats 12—14, which extend in parallelism and transversely beneath the bar.

Preferably, the wings 10—13 are left remaining in the planes of their respective flanges 2—2 at the time of manufacture of the devices, so as to enable the compact packing of the devices closely in and upon one another in a nested position, such as shown 100 in Fig. 3, for the conservation of space in storage and in transportation; it being but a simple matter for a laborer on the job where the devices are to be erected, to apply a suitable tool to the wings to bend them from the position shown in Fig. 2, to the position 105 shown in Fig. 1, ready for use.

There is shown in Figs. 4 and 5, a slightly modified form of the supporting clip in which one of the side panels 2—2 is provided with a bar supporting shoulder, as 14^a, which is produced by cutting a re-entrant notch 15 inwardly in the flange from the angle 6, the other flange 2 being provided with an elongated slot 16, forming a tongue 17, disposed between the bottom edge 18 of the slot 16 and the outer edge of the flange. The flange 2, in which the notch 15 is formed, is extended upwardly substantially full width, while the tongue 17 is less than the width of its flange 2 by an amount equal to the slot 16. A reenforcing bar A' may be inserted in the notch 15 and will rest upon the transverse shoulder, or seat 14^a, after which the tongue 17 is folded 110 115 120 125 130

- along a line 17^a over the top of the bar and then is again folded on the line 17^b down over the inner face of the bar, and finally folded along the line 17^c in under the bar.
- 5 The upper bar B' may then be placed transversely across the lower bar B, which forms a support therefor, and the upper end of the flange 2 above the notch 15 may be folded along the line 18 over the top of the bar B' and again folded along the line 19 down over the inner face of the bar B'. It is obvious that the foot-forming flanges 3 at the lower end of the support may be folded outwardly as in Fig. 1, or may be 15 folded inwardly as in Fig. 5.
- The foot flanges 3 may have punched therein tack-like prongs or points T. The tack-like points are preferably arranged with their planes parallel so as to be readily 20 driven into the wood form or box.
- What is claimed is:—
1. A chair for supporting re-enforcing rods, comprising a standard having angularly folded, longitudinal flanges and being slotted inwardly from one end along the hip of the fold, the bottom of the slot forming transverse seats, at right angles to each other, for rods; the separated ends of the flanges constituting wrapping means to be 25 folded around an applied rod.
  2. A chair for supporting re-enforcing rods, comprising a standard having angularly folded, longitudinal flanges and being slotted inwardly from one end along the 30 hip of the fold, the bottom of the slot forming transverse seats, at right angles to each other, for rods; the separated end of the flanges constituting wrapping means to be folded around an applied rod, the rod seats 35 being longitudinally offset.
  3. A chair for supporting re-enforcing rods, comprising a standard having angularly folded, longitudinal flanges and being slotted inwardly from one end along the hip of the fold, the bottom of the slot forming 40 transverse seats, at right angles to each other, for rods; the separated end of the flanges constituting wrapping means to be folded around an applied rod, the rod seats 45 being longitudinally offset.
- other, for rods; the separated ends of the flanges constituting wrapping means to be folded around an applied rod, and the flanges having the edges rebated to form 50 transverse shoulders and notched to form wings adapted to be folded in across an applied rod.
4. A chair for supporting re-enforcing rods, comprising a plate bent along a longitudinal line to form vertical angular flanges, the chair being slotted inwardly along the hip from its upper end to form transverse bottom edges, one in each flange, which constitute seats for rods. 55
5. A chair for supporting re-enforcing rods, comprising a plate bent along a longitudinal line to form vertical angular flanges, the chair being slotted inwardly along the angle hip from its upper end to form transverse bottom edges which constitute seats for rods which are movable inwardly through the mouth of the slot, the whole flanges above the seats constituting tongues bendable over inserted rods. 60
6. A chair for supporting re-enforcing rods, comprising a plate bent along a longitudinal line to form vertical angular flanges, the chair being slotted inwardly along the angle hip from its upper end to form transverse bottom edges which constitute seats for rods which are movable inwardly through the mouth of the slot, the upper corner edges of the flanges having wings foldable around to form rod seats. 65
7. A chair for supporting re-enforcing rods, comprising an angle-iron standard having a slot extending along the angle hip of the standard and extending laterally into each flange but terminating at different 70 points in each so as to form rod seats for rods in superposed relations and crossing each other.
- In testimony whereof, I have hereunto set my hand.

CHRISTOPHER HENRY SNYDER.
